UNITED STATES PATENT OFFICE.

LEWIS C. BROOKS, OF MILWAUKEE, WISCONSIN. ASSIGNOR TO THE NATIONAL PAPER CAN COMPANY, OF MILWAUKEE, WISCONSIN, A CORPORATION OF WISCONSIN.

CONTAINER.

Application filed November 25, 1921. Serial No. 517,506.

To all whom it may concern:

Be it known that I, LEWIS C. BROOKS, a citizen of the United States, residing at Milwaukee, county of Milwaukee, and State 5 of Wisconsin, have invented a new and useful Improvement in Containers, of which the following is a full, clear, and exact description.

The present invention relates to containers and more particularly to containers having readily removable closures to allow the inspection required by the postal authorities for matter sent through the mails.

The object of the present invention is to 10 produce a container of this character which can be made cheaply and which, although the closure is readily removable, the closure will be held securely.

In the illustrated embodiment of the invention, Figure 1 is a perspective view of a container embodying the present invention with the closure removed;

Figure 2 is a perspective view of the closure showing the string-attaching nob;

Figure 3 is a view of the closure 4 before the application to it of the string-attaching nob;

Figure 4 is a perspective view of the completed package;

Figure 5 is a vertical section through the container shown in Figure 4; and

Figure 6 is a vertical section showing a modification.

Referring to the illustrated embodiment 35 of the invention, the container 1 is shown as the usual can or tube, preferably made of paper or other light material.

A closure 2 is permanently applied to the bottom in any suitable way.

The closure 3 is removably applied to the upper end or mouth of the container. This closure 3 is shown as a snap disk which is inserted in the mouth of the container and is seated against an annular internal bead 40 or seat 4. This seat is shown in the illustrated embodiment as formed by beading in the body of the container, but may be otherwise formed. The mouth of the container is continued at 5 above the closure. The edge 45 above the closure is provided with notches 6, preferably cut at an angle, as shown in Figures 1 and 4. These notches serve as a string-retaining means on the container body. The closure 3 has suitable string-se-

curing means illustrated as a nob formed by 50 55

the ordinary paper fastener which is inserted through the middle of the closure. A string 8 is secured to the nob 7. The closure 3 is applied by inserting it in the mouth of the container against the seat 4. Then 60 the string, one end of which is attached to the nob 7, is passed through one of the notches 6, wound once or twice around the container in the groove 9 and then passed through the other notch 6 and wound around 65 the nob. The closure may be easily removed by unwinding the string and then replaced, thus permitting the easy inspection of the contents required by the postal authorities. 70

In Figure 6 is illustrated a modification. As shown in Figure 6, the can body is not beaded in as shown in the other figures, but is left straight at its mouth. The disk 3 is forced into the mouth of the can thus forcing out a little ridge 10 around the can body. The string 8 is passed through notches 6 in the can body and wound around underneath the little ridge 10 formed by the outward pressing of the can body by the disk closure. 75 80

It is to be understood that the present invention is not limited to its illustrated embodiment but may be otherwise embodied within the scope of the following claims.

I claim:

1. A container having a mouth, a closure for the mouth, string-retaining means for the exterior of the container, and a string for removably holding the closure in place passing over the top of the closure and engaging the string-retaining means on the container, said string being entirely exterior of the closure and container, substantially as described. 85 90

2. A container having a mouth, a closure for the mouth, notches in the container and string-securing means on the closure, both exterior of the closed container, and a string attached to the string-securing means and passing through the notches, substantially 100 as described.

3. A container having a body portion with an internal annular flange, a disk closure seated against the internal flange, the container body having notches therein above the 105 closure, string-securing means on the closure, and a string attached thereto and passing through the notches, substantially as described.

4. A container having a mouth, a closure 110

adapted to fit therein, notches above the mouth and exterior of the closed container, and a string secured to the exterior of the closure and passing through the notches. 20

5. A container having a mouth provided with a seat, a closure for the mouth resting on the seat, a string-retaining groove in the outer surface of the container, and a closure-retaining string lying entirely outside the 10 closed container and across the top of the closure, said string being attached to the closure and wound around in the string-retaining groove, substantially as described.

6. A container having a body portion with 15 an internal annular seat and an external groove at its mouth, a closure fitting internally into the container mouth and seating against the seat, string-retaining means at the edges of the can body above the closure,

string-retaining means on the closure, and a string secured to said several string-retaining means for holding the closure in place, substantially as described.

7. A container having a body portion with an internal annular seat and an external groove at its mouth, a closure fitting internally into the container mouth and seating against the seat, the edge of the can body above the closure being formed with string-retaining notches, a string-retaining nob on the closure and a string passing around the nob and through the notches for removably holding the closure in place, substantially as described. 25 30

In testimony whereof I have hereunto set 35 my hand.

LEWIS C. BROOKS.
